CLAIM

The ornamental design for a display screen with animated graphical user interface, as shown and described.

DESCRIPTION

FIG. 1 is a front view of a first image of a display screen with animated graphical user interface showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; and, FIG. 9 is a front view of a ninth image thereof.

The appearance of the image sequentially transitions between the images shown in FIGS. 1-9. The process or period in which one image transitions to another image forms no part of the claimed design.

The outermost broken lines of short even length shown in the drawing illustrate a display screen and form no part of the claimed design. The remaining broken lines of short even length illustrate portions of the animated graphical user interface that form no part of the claimed design.

1 Claim, 9 Drawing Sheets
